UNITED STATES PATENT OFFICE.

GEORGE NORMAN SCOTT, OF WEST NEW BRIGHTON, NEW YORK, ASSIGNOR TO BETHLEHEM SHIPBUILDING CORPORATION, LTD., A CORPORATION OF DELAWARE.

OIL-BURNING ATTACHMENT FOR FURNACE FRONTS.

Application filed June 7, 1923. Serial No. 644,021.

The present invention relates to oil burning attachments for furnace fronts.

It is frequently desirable to convert a coal burning furnace into an oil burning furnace, and it is the object of the present invention to provide an attachment whereby this conversion may be brought about quickly and conveniently or the reverse accomplished, that is, the detachment or disassembling of the oil burning mechanism so that the furnace may be again adapted for the consumption of coal or other solid fuel. The invention embodies a number of novel features including, among others, a novel furnace ring construction, novel means for mounting the oil spray or nozzle for adjustment relatively to the furnace ring and for removal, a novel arrangement of the valve controlling the flow of atmospheric air to the combustion space. Other features of novelty will be disclosed in the specification and drawings, and particularly pointed out in the appended claims.

In the drawings:

Figure 1 is a front elevation of the oil burning attachment.

Figure 2 is a vertical axial section through the same and through the adjacent portion of the furnace to which it is attached.

Figure 3 is a horizontal axial section through the attachment and adjacent portion of the furnace, and

Figure 4 is a front elevation of the furnace attachment with the main portion or casing removed.

The face of the boiler, which may be of any well known type, either marine or stationary, is indicated at 10 and the wall of the fire box at 11. In converting a furnace from a coal to an oil burning furnace it is first necessary to reduce the inlet opening of the fire box. Refractory brick work for this purpose is indicated at 12 and the refractory furnace ring at 13, the entire amount of air entering the furnace passing through the aperture in this ring so that the effective air inlet opening is greatly reduced as compared with the original fire box opening. The ring is made in four quarter sections, as shown in Figure 4, for convenience in manufacture and to increase the length of life of the ring in actual use. There is considerable expansion and contraction of the ring due to variations in temperature at the mouth of the fire box, and this expansion

and contraction occurs without straining or distorting any part of the sectional ring, the joints between the sections permitting such movement to freely occur. The adjacent edges of the sections of the ring are provided with aligned or registering slots 14, and into each pair of registering slots extends the end of an S-shaped lug 15, the outer ends of these lugs being secured by bolts to the false plate F. This false plate comprises two portions, the upper portion 16 and the lower portion 17, the abutting horizontally extending flanges of which are secured together by bolts 18. A central aperture in the false plate is indicated at 19 and this aperture is co-axial with the opening in the furnace ring. It will be seen that the sections of the furnace ring are secured by the S-shaped lugs 15 to the false plate in such manner that the ring may be inserted and removed as a unit, and is held against inward displacement by this member.

Secured to the front of the fire box 11 is the casing 20 of generally cylindrical form, which supports the oil spraying device and the valves controlling the flow of air to the same. The furnace forced draft air duct (not illustrated) is adapted to bring or convey air under pressure to the casing above the transverse partition 21 at its top, which partition is provided with the air port 22 controlled by slide valve 23. This valve may be moved horizontally by means of an arm 24 mounted upon an arbor 25 adapted to be rotated by a crank arm and handle secured thereto and without the casing. Air passing under forced draft through port 22 finds its way through apertures 26 into the interior of the casing and thence through the furnace ring into the fire box. A door 30 hinged at 31 to swing about a horizontal axis controls the port provided for the entrance of atmospheric air, this door being provided with latches L by means of which it may be locked in closed position. A second door is indicated at 32 and is hinged at 33 to swing about a vertical axis. It is normally held in closed position by a latch 34 which engages a catch 35 secured to the casing. This door 32 is provided with a peephole or torch hole 36 normally closed by a shutter 37 and is provided with an aperture 38 through which the nozzle supporting tube 39 extends.

Tube 39 is slidably supported in a bear-

ing member 40 mounted on coaxial bearing axles 41, the outer ends of which rest in suitable pocket or notches 42 in bearing blocks 43 bolted to the casing. A post 44 projects rearwardly from the door 32 and extends through an aperture in a lug 45 mounted on a collar 46 secured to the rear end of the nozzle supporting tube 39. A set screw 47 extends through an aperture in 10 lug 45 so that its inner end may engage post 44 to secure the nozzle supporting tube 39 in any desired position of axial adjustment. The arrangement is such, however, that tube 39 may be tilted about its transverse axis of 15 support so that the burner nozzle may have the desired relationship to the furnace ring. This tilting is accomplished by means of an adjusting screw 50 which extends through a threaded aperture in the casing and engages 20 a lug 51 extending downwardly from the bearing block 40. Lug 51 and adjusting screw 50 are maintained in constant engagement because of the tendency of the combustion tube 39 to tilt in a clockwise direction 25 (Fig. 2), due to the greater weight of its inner end, to which the slotted burner cone is secured.

The application of the attachment to a furnace involves, as previously pointed out, 30 the insertion of the refractory brick work, the furnace ring, and the attachment of the casing, all of which may be done in a relatively short time. The grate of the furnace may be removed when the oil burning attachment is installed, or the grate may be covered with brick known to the art. To 35 reconvert the furnace for the use of solid fuel it is only necessary to remove the oil burning equipment, furnace ring, and replace the grate.

One skilled in furnace design and operation will appreciate the advantages of the invention disclosed and will realize that the design and arrangement of its component 45 elements may be considerably changed without departing from its spirit and scope.

Having thus described the invention what is claimed as new and desired to be secured by Letters Patent is:

50 1. A furnace attachment of the class described comprising a furnace ring formed of segmental sections of refractory material, a plate member having an aperture co-axial with that of the ring, and means carried by 55 the plate member for engaging the sections peripherally in order to hold the latter in place as a unit with respect to the plate member.

2. A furnace attachment of the class described, including in combination, a furnace

ring formed in segmental sections, the abutting ends of the respective sections being provided with aligned slots, a supporting member, and means connecting the ring sections to the supporting member including 65 brackets secured to said member and having portions extending within said slots, each bracket thereby engaging two of said sections.

3. A furnace attachment of the class described comprising a furnace ring formed of segmental sections of refractory material, a plate construction consisting of a plurality of parts which, when assembled, form an aperture co-axial with that of the furnace 75 ring, means for securing the plate parts together, and brackets carried by the plate parts and engaging the segmental sections to hold the latter in place as a unit with respect to the plate construction. 80

4. A furnace attachment of the class described comprising a furnace ring formed of segmental sections of refractory material having registering peripheral depressions at adjacent ends thereof, a plate construction 85 consisting of a plurality of parts which, when assembled, form an aperture co-axial with that of the furnace ring, means for securing the plate parts together, and brackets carried by the plate parts and engaging in the peripheral depressions of the segmental sections to hold the latter in place as a unit with respect to the plate construction. 90

5. A furnace attachment of the class described comprising a furnace ring formed of segmental sections of refractory material, a plate construction consisting of upper and lower parts which, when assembled, form an aperture co-axial with that of the furnace 100 ring, means for securing the plate parts together, and brackets connected to the plate parts and engaging the segmental sections peripherally to hold the latter in place as a unit with respect to the plate construction. 105

6. A furnace attachment of the class described, including in combination, a furnace ring having separate segmental sections, a supporting member arranged forwardly of the ring, and means connecting the ring to the supporting member including brackets secured to said member and having portions engaging recesses in the periphery of the ring sections whereby said brackets are held between the furnace ring and the furnace 110 wall when in assembled relation. 115

In testimony whereof I hereunto affix my signature.

GEORGE NORMAN SCOTT.
